Specification for Design.

Patented May 16, 1916.

Application filed May 25, 1914. Serial No. 840,948. Term of patent 7 years.

To all whom it may concern:

Be it known that I, EDMUND HOFFMAN, a citizen of the United States, residing at Brooklyn, in the county of Kings and State of New York, have invented a new, original, and ornamental Design for Talcum-Powder-Box Tops, of which the following is a specification, reference being had to the accompanying drawing, forming a part thereof.

In the drawing, Figure 1 is a top plan view of a box top embodying my invention.

Fig. 2 is a side elevation of the same and Fig. 3 is a transverse, central, vertical, sectional view of the neck and cap portion of the box top.

I claim:

The ornamental design for a talcum powder box top, as shown.

EDMUND HOFFMAN.
